his Attorney.

UNITED STATES PATENT OFFICE.

ROWLAND H. WOLFE, OF CHICAGO, ILLINOIS.

CAN-OPENER.

1,374,702.

Specification of Letters Patent. Patented Apr. 12, 1921.

Application filed July 3, 1918. Serial No. 243,166.

To all whom it may concern:

Be it known that I, ROWLAND H. WOLFE, a citizen of the United States, and a resident of the city of Chicago, county of Cook, and 5 State of Illinois, have invented certain new and useful Improvements in Can-Openers, of which the following is a specification.

My invention relates to improvements in can openers, and has for its object the provision of an improved construction of this 10 character which is simple and efficient in use.

Other objects will appear hereinafter.

The invention consists in the combinations and arrangements of parts hereinafter 15 described and claimed.

The invention will be best understood by reference to the accompanying drawings forming a part of this specification, and in 20 which,

Figure 1 is a bottom plan view of a can opener embodying the invention,

Fig. 2, a transverse section thereof, taken substantially on line 2—2 of Fig. 3,

25 Fig. 3, a longitudinal section of the can opener, and

Fig. 4, a detailed view of a cutting wheel and its mounting employed in the construction.

30 The preferred form of construction, as illustrated in the drawings, comprises a supporting member 5 made of a strip of heavy sheet metal bent into transversely curved channel form, with the extreme end 6 there- 35 of bent downwardly to close the end of said channel and provided with a downwardly and longitudinally extending piercing point 7 adapted to serve as a pivot for the can opener in the usual manner. At its other 40 end the supporting member is provided with a handle 8, as indicated. The supporting member 5 is also provided with a longitudinal slot 9 located at the bottom of the channel formation thereof, and a saddle or 45 carriage 10 is slidably mounted on the outside of member 5, being curved to conform thereto, and provided with lips 11 sliding on the edges of member 5. The saddle mem- 50 ber 10 is provided with downwardly extend- 55 ing mounting lugs or ears 12 projecting through the slot 9, and a cutting wheel 13 is rotatably mounted between said ears by means of a machine screw 14 extending loosely through one of said lugs and thread- ed in the other, as indicated in Fig. 3. By this arrangement the cutting wheel 13 may

be readily adjusted longitudinally on the supporting member 5 to suit different sizes of cans and then employed to remove the top of the can by inserting the point 7 at the center thereof and swinging the cutting wheel around the edge of the can while pressing downwardly thereon. As indicated, the cutting wheel 13 is arranged with in the channel member 5 with a cutting edge 60 projecting therefrom and whereby the wheel is partially protected and concealed within the channel member, and the general construction of the opener greatly stiffened and straightened.

70 While I have illustrated and described the preferred form of construction for carrying my invention into effect, this is capable of variation and modification without departing from the spirit of the invention. I therefore, do not wish to be limited to the precise details of construction set forth, but desire to avail myself of such variations and modifications as come within the scope of the appended claims.

80 Having described my invention, what I claim as new and desire to secure by Letters Patent is:—

1. A can opener comprising a supporting member, provided with a longitudinal slot; 85 a saddle sliding upon said supporting member; mounting ears on said saddle projecting through the slot in said supporting member, and a cutting wheel rotatably mounted between ears, substantially as de- 90 scribed.

2. A can opener, comprising a trans- 95 versely curved channel member, provided with a longitudinal slot at the bottom of the channel; a saddle curved to fit the curvature of said channel member and sliding upon the outer side thereof; mounting ears on said saddle member, projecting through the slot in said channel member; and a cutting wheel rotatably mounted between said ears 100 and resting partially within said channel member with its edge projecting therefrom, substantially as described.

3. A can opener comprising a channel member closed at one end, and provided with a longitudinal slot at the bottom of the channel therein; a point at the closed end of said member; a handle at the other end of said member; a saddle mounted to slide upon the outer side of said channel member 105 and provided at its edges with lips sliding on the edges of said channel member;

mounting ears on said saddle member projecting through the slot in said channel member; and a cutting wheel rotatably mounted between said ears and resting partially within said channel member with its edge projecting therefrom, substantially as described.

In testimony whereof I have signed my name to this specification in the presence of two subscribing witnesses.

ROWLAND H. WOLFE.
